(57) **CLAIM**

The ornamental design for a vacuum cup, as shown and described.

DESCRIPTION

FIG. 1 is a front perspective view of a vacuum cup, showing my new design;
FIG. 2 is a rear perspective view thereof;
FIG. 3 is a front view thereof;
FIG. 4 is a rear view thereof;
FIG. 5 is a left side view thereof;
FIG. 6 is a right side view thereof;
FIG. 7 is a top view thereof;
FIG. 8 is a bottom view thereof;
FIG. 9 is an enlarged detail view of area 9 in FIG. 2; and,
FIG. 10 is an enlarged detail view of area 10 in FIG. 2.
The dash-dot-dash broken lines represent boundaries of the enlarged portion that form no part of the claimed design.
The broken lines in the drawings depict portions of the vacuum cup that forms no part of the claimed design.

1 Claim, 10 Drawing Sheets(56)
